(57) **CLAIM**

The ornamental design for a cap, as shown and described.

DESCRIPTION

FIG. 1 is a front perspective view of a cap in accordance with a preferred embodiment of my new design;

FIG. 2 is top plan view thereof; and,

FIG. 3 is a front elevation view thereof, left-side, rear, and right-side elevational views being identical.

The bottom plan view of the cap is not shown in the drawings or described in the specification and, therefore, forms no part of the claimed design.

The broken lines in the figures are for illustrative purposes only and form no part of the claimed design.
